WILFRED SHUTTLEFF, OF MOLINE, ILLINOIS, ASSIGNOR TO MOLINE HEAT, OF MOLINE, ILLINOIS, A CORPORATION OF ILLINOIS.

DIFFERENTIAL CHECK-VALVE FOR RADIATORS.

1,287,119.

Specification of Letters Patent. Patented Dec. 10, 1918.

Application filed May 18, 1915. Serial No. 28,848.

To all whom it may concern:

Be it known that I, WILFRED SHUTTLEFF, a citizen of the United States, residing at Moline, in the county of Rock Island and

5 State of Illinois, have invented a new and useful Improvement in Differential Check-Valves for Radiators, of which the following is a specification.

In the present practice of steam heat installation, especially that of the two-pipe system, it is essential to provide a globe or cut-off valve at both the steam inlet side and also at the steam return or discharge side so that all communication of the radiator with

10 the steam pipe lines may be severed when it is desired to cool the radiator.

In certain modifications of the two-pipe system, a valve is provided at the steam inlet side and either a swing-check or ball-check 20 valve at the outlet side of the radiator which valve acts as a check against the return of the steam into the radiator.

It has, however, been found from experience that this method of preventing the re-entrance of the steam to the radiator is unreliable for the reason that an ordinary 25 check valve will not close sufficiently tight to serve this purpose and steam can therefore re-enter the radiator, assuming the inlet valve to have been closed.

Therefore, the object of my invention is to provide a fluid operated back-check valve which is to be connected in the return or steam discharge pipe of a radiator of the 30 two-pipe system which back-check valve will positively prevent the entrance of steam into the radiator from the return side of the pipe line after the inlet valve in the steam inlet side has once been cut off.

40 A further object of my invention is to provide a valve in the steam discharge or return pipe which will be susceptible to an opening movement when the valve in the steam inlet pipe is opened, this function being obtained by the slight excess pressure 45 of steam in the inlet side over that in the outlet side thus allowing any water of condensation or air present within the radiator to be discharged into the return or discharge 50 pipe.

In order that the aforesaid objects may be accomplished, I provide a valve casing connectible in the return side of a two-pipe steam heating system, at the top of which 55 casing is clamped a flexible diaphragm of

relatively large area which diaphragm in turn carries a pendent closure valve which co-operates with a suitable valve seat formed in the body of the casing.

In the normal operation of the radiator or 60 when the inlet valve is open and the steam pressure is on, the aforesaid valve contained in the valve casing is raised or opened, this being caused by the pressure of the incoming steam acting on the underside of the 65 diaphragm from which the valve is pendent, thus keeping the valve raised from its seat and establishing a through passage for the steam.

Should the steam inlet valve be suddenly 70 closed, a rapid condensation of the steam within the radiator will result, causing a partial vacuum to form; and since the pressure in the return pipe is now in excess of that in the radiator, the steam in the return 75 pipe will tend to rush into the radiator thus causing a re-heating of it.

To obviate this, the stem of the pendent valve is provided with an aperture communicating with the chamber above the diaphragm through which aperture steam will enter filling the chamber thus allowing pressure to be distributed over the area of the diaphragm and consequently reseating the valve. 85

The invention also resides in these novel details of construction, combination and arrangement of parts, all of which will be hereinafter fully explained and then specifically pointed out in the appended claim, 90 reference being had to the accompanying drawing in which:—

Figure 1 is a diagrammatical representation of a steam heating system of the two-pipe type showing my invention applied to 95 the steam return pipe.

Fig. 2 is a central vertical section of the back-check valve which is the object of my invention, the valve being closed in full lines and open, in dotted lines. 100

Fig. 3 is a sectional view of the lower part of the valve structure showing the valve raised.

Referring now to Fig. 1, 1 is the steam inlet pipe of a heating system of the usual two-pipe type which pipe 1 is common to a plurality of radiators 2, while 3, indicates the steam return or discharge pipe which carries the steam back to the source of supply. 110

Connected between the inlet pipe 1, and the individual radiator 2, is a cut-off valve 4, by which the steam may be turned off or on to effect the cooling or the heating of the radiator.

Oppositely to the inlet valve 4, and connected in the return pipe 3, of the system is a check valve 5, the detailed operation of which will presently be explained.

- 10 The valve 5, merges at its upper extremity, with a semi-globular portion 6, which in turn is flattened horizontally to form a circumferential flange 7, between which and the corresponding flange of a cover 8, a flexible diaphragm 9 of relatively large area, is fixedly clamped. 10 is a gasket which renders the chamber 11, above the diaphragm 9, steam-tight as well as preventing escape of steam from the interior 20 of the valve 5.

Connected pendently from the diaphragm 9, as at 12, is a stem 13, at the bottom of which is formed a valve which is adapted to engage a suitably ground seat in the 25 steam discharge port 15 of the valve 5. Arranged vertically in the stem 13, is a bleeder passage 16 which offers communication between the chamber 11 and with the discharge pipe 3 and interior of the valve 5, alternately.

By providing the diaphragm 9 of relatively large area and a bleeder passage of small diameter through the stem 13 of the valve 14, a differential valve with a large 35 area at the top of same is provided thus affording additional pressure to insure the closing of the valve 14 at certain times when this is desirable.

In the normal operation of the system 40 with the valves 4 open, steam is being admitted into the radiators, and in passing outwardly toward the discharge pipe, pressure is exerted against the underside of diaphragm 9 thus raising valve 14 from its 45 seat a short distance whereupon the steam rushes between the valve and seat and through the restricted port 15 into the outlet 3. Such flow causes a void *v* at the lower end of the passageway 16 and automatically 50 removes pressure from the passageway 16 and chamber 11. In other words, a suction effect is caused below the passageway 16 which is communicated to the upper diaphragm chamber 11 and assists in holding 55 the valve raised. The weight of the valve is always acting on the steam flowing between it and the seat and causes maintenance of the void *v*.

Should one of the valves 4 be suddenly

closed, a rapid condensation of the steam 60 within the radiator will result and cause a partial vacuum to form and in turn produce a pressure of less degree in the radiator than in the return pipe 3 which would naturally cause the discharge steam to return to the 65 radiator causing the undesirable re-heating. By reason of the provision of the bleeder passage 16 in the stem of valve 14, steam will collect in the chamber 11 and exert a 70 great pressure over the large area of the diaphragm in chamber 11 thus causing valve 14 to be re-seated, this being accomplished quickly because of the difference in pressure in the radiator and the return or discharge pipe.

75 Thus, the higher the pressure in the discharge pipe 3 and the lower the pressure in the radiator 2, the more pressure will be brought to bear against the diaphragm 9 and consequently the valve seat 15 thus insuring an absolute seal against the return of the steam into the radiator from the discharge pipe line.

What I claim is:—

In a check valve for preventing the back 85 heating of a steam radiator, the combination of a casing having a valve chamber and an inlet and an outlet for said chamber, there being a restricted valve port between said inlet and outlet, a valve seat surrounding 90 said port, the upper end of said casing being expanded, a diaphragm extending transversely across said expanded upper part to divide such part into an upper diaphragm chamber and a lower diaphragm chamber, 95 said lower diaphragm chamber being at all times in communication with said valve chamber, a valve suspended from said diaphragm and free to move downwardly with the diaphragm to engage said valve 100 seat to close said port, said diaphragm being entirely free to be raised to unseat the valve when the pressure at said inlet is greater than that at the outlet, said valve having a restricted passageway extending lengthwise 105 therethrough for connecting said outlet with the upper diaphragm chamber when the valve is down and in closed position, said valve chamber being disconnected from the upper diaphragm chamber when the valve 110 is closed, said valve being held closed by the pressure in the upper diaphragm chamber when the pressure at said outlet is greater than at said inlet.

WILFRED SHURTLEFF.
